UNITED STATES PATENT OFFICE.

JOSEPH E. LE DUC, OF NORTHAMPTON, MASSACHUSETTS, ASSIGNOR OF ONE-THIRD TO TERRANCE LAWLER AND LUDOLPH NEHRING, OF SAME PLACE.

CIGAR-CLIPPER.

SPECIFICATION forming part of Letters Patent No. 598,634, dated February 8, 1898.

Application filed May 14, 1897. Serial No. 636,553. (No model.)

To all whom it may concern:

Be it known that I, JOSEPH E. LE DUC, of Northampton, (Florence,) in the county of Hampshire and State of Massachusetts, have 5 invented certain new and useful Improvements in Match-Safes and Cigar-Clippers; and I do hereby declare the following to be a full, clear, and exact description of the invention, such as will enable others skilled in the art to 10 which it appertains to make and use the same.

This invention relates to match-boxes, and has for its object to provide a simple, cheap, and efficient match-box in which a movable object or figure is employed adapted when 15 moved in a certain way to pick up a single match at a time and hold the same in a convenient position to be grasped by the hand. The match-box also embodies a cutter or clipper for removing the ends of cigars, said cutter being operated simultaneously with the 20 movement of the figure.

The detailed objects and advantages of the invention will appear in the course of the subjoined description.

25 The invention consists in certain novel features and details of construction hereinafter specifically set forth, illustrated in the drawings, and incorporated in the claim hereto appended.

30 In the accompanying drawings, Figure 1 is a perspective view of a match-safe constructed in accordance with the present invention. Fig. 2 is a longitudinal section through the same. Fig. 3 is a transverse sectional view 35 thereof.

Similar numerals of reference designate corresponding parts in the several views.

The improved match-safe contemplated in this invention comprises two side portions 1, 40 which extend longitudinally of the safe and form the sides of the match-receptacle. Each of said sides is substantially V-shaped, or, in other words, the sides comprise upwardly-converging upper portions 2 and downwardly-converging lower portions or walls 3, whereby the matches placed in the receptacle are caused to gravitate to a common central point (indicated at 4) forming the lower vertex of the match-receptacle.

45 Each of the sides is provided with two or more supporting-legs 5, which are preferably

cast or formed integrally with the sides of the safe, and these legs are preferably provided with rubber bumpers or cushions on their lower ends to prevent the device from 55 marring the counter or other piece of furniture upon which the device is placed. The side portions 1 of the safe are provided at their upper ends with flaring lips 6 for insuring the movement of the end of the match- 60 picking device into the receptacle.

The sides 1 of the safe are extended in rear of or at one end of the match-receptacle, as shown at 7, and provided with upwardly-extending ears 8 to receive a transverse pin 9, 65 upon which is fulcrumed a movable object 10, the object illustrated in the drawings being in the form of a man having one arm extended and carrying a match-picking device in the form of a spear, as shown at 11. 70

The object or figure is provided with a depending arm or lever 12, which extends downward between the portions 7 of the safe, where it has connected to it one end of a contractile coiled spring 13, the opposite end of which is secured to a fixed point 14 on the rear wall of the match-receptacle 1, said spring serving to retract the figure to an upright position after said figure has been moved forward for the purpose of picking up a match or severing the end of a cigar. Attached to the figure or object 10 and extending forward therefrom is a cutter 15, which operates behind an opening 16 in a cheek or extension 17 of one of the portions 7 of the safe, so that upon inserting the end of a cigar in the opening 16 and vibrating the figure 10 the cutter will remove the end of the cigar, which projects through the opening in a manner readily understood. The front wall of the match-receptacle is curved, as indicated at 18, in the arc of a circle, of which the pivot of the figure is a center. 90

Secured to the end of the spear 11 is a match catcher or picker 19 in the form of a spring. 95 This spring is formed from a single piece of wire, the terminal portions of which are inserted in the end of the spear or otherwise suitably connected thereto. The portion of the spring intermediate its ends is given two complete coils, thus forming oppositely-located and substantially parallel circular

spring jaws or clasps 20, which are adapted to yield apart as the spear descends into the match-receptacle, so as to embrace the stem of a match and clasp the same with sufficient tension to enable the match to be raised when the figure 10 is restored to its normal position by the spring 13 after the figure is released, it being understood that the figure is depressed by the hand of the operator.

21 designates a hinged door for giving access to the rear of the compartment in which the spring and lower portion of the figure are located.

The match-safe above described is quite simple in construction, comprises but few parts, which may be cast, with the exception of the cutter and the springs, and may be manufactured at correspondingly low cost.

In operation the tip end of a cigar is placed 20 in the opening 16 and the figure 10 then rocked. In this movement the end of the cigar is cut off and the spear enters the match-receptacle and engages a match, so that upon releasing the pressure upon the figure the

spring serves to restore the same to its normal position and also lift the match above the top of the receptacle, where it is in convenient position to be taken from the spring-clasp by the operator.

Having thus described the invention, what is claimed as new, and desired to be secured by Letters Patent, is—

A match-box comprising a match-receptacle, a normally upright part pivoted adjacent to the receptacle, and carrying a spring-clasp 35 for the withdrawal of a match, and an integral downward extension and a lateral cigar-cutting extension, and a spring attached to one end of the downward extension and to the receptacle, for restoring the part to its upright position.

In testimony whereof I have signed this specification in the presence of two subscribing witnesses.

JOSEPH E. LE DUC.
